UNITED STATES PATENT OFFICE.

WALTER W. BROWN, OF SCHENECTADY, NEW YORK, ASSIGNOR TO GENERAL ELECTRIC COMPANY, A CORPORATION OF NEW YORK.

ELECTROMAGNET.

No. 826,307.

Specification of Letters Patent.

Patented July 17, 1906.

Application filed January 9, 1905. Serial No. 240,198.

To all whom it may concern:

Be it known that I, WALTER W. BROWN, a citizen of the United States, residing at Schenectady, in the county of Schenectady and State of New York, have invented certain new and useful Improvements in Electromagnets, of which the following is a specification.

My invention relates to electromagnets of the type disclosed in a former patent, No. 765,550, issued to me July 19, 1904; and it consists of an improvement in the arrangement described therein.

In my former patent I described an electromagnet adapted for use in block-signal systems for holding the signal at clear position. In order to economize current, the magnet is provided with a latch for holding the operating mechanism in position when raised, so as to take the weight from the core of the magnet, and with a switch arranged to decrease the current flowing through the magnet to an amount merely sufficient to support the core alone. When the magnet is wholly deenergized, the core drops and trips the latch, allowing the operating mechanism and signal to go to "danger." This arrangement obviously results in a material saving of current, since the full current is required only while the signal is being moved to clear position. The moving parts of the operating mechanism are preferably provided with a retarding device in order to prevent too sudden movements and jars of the operating mechanism. I have now found that if the switch controlling the circuit of the electromagnet is operated directly by the operating mechanism, as shown in my former patent, it results that a slow break is obtained when the switch opens, which results in more or less arcing. This not only produces deterioration of the contacts, but also, if the arc is drawn out to any appreciable length before breaking, the current in the magnet-winding is decreased gradually, whereas it is desirable that it should be decreased suddenly at the instant the latch is in proper position for engagement. With a gradual decrease of current-flow through the magnet it is difficult to so adjust the magnet-winding that the operating mechanism is released at the instant that the latch is in proper position for engagement. If the decrease of current does not begin until the

latch is in proper position, it will be carried an appreciable distance beyond its proper position before the operating mechanism is released by the magnet. Thus not only is power wasted in moving the mechanism an unnecessary distance, but also the mechanism may acquire sufficient momentum in dropping back to its proper position to trip the latch and prevent its engagement. On the other hand, if the gradual decrease of current is begun before the latch has reached its proper position the magnet must be made large enough to insure the continuance of the movement on the decreased current until the proper position is reached. By providing means for obtaining a quick break at the exact instant when the latch has reached the proper engagement the above considerations are eliminated and the efficiency and reliability of operation are increased.

My present invention therefore consists in providing means for obtaining a quick and positive movement of the switch in the magnet-circuit, regardless of the rate of movement of the operating mechanism.

More specifically considered, my invention consists in arranging the switch operated by the moving parts of the magnet to control the circuit of a relay, which in turn controls the circuit of the operating-magnet.

In one aspect my invention is not limited to the particular construction or mechanism described in my former patent, but consists, broadly, in the combination of a movable member, an electromagnet for moving the member, a switch arranged to be operated when the member is moved, and a relay controlled by the switch adapted to decrease the current through the magnet.

My invention will best be understood by reference to the accompanying drawings, in which—

Figure 1 shows a side elevation of an electromagnet of the type disclosed in my former patent. Fig. 2 is a diagram of connections. Fig. 3 is a cross-sectional view of a relay adapted to control the circuit of the electromagnet.

The operating-electromagnet shown in Fig. 1 is fully described in my former patent, above referred to, but in order to present my present invention clearly will be described here. A represents the operating-magnet, which is shown as a solenoid provided with

vertically-movable core B. Core B has at its lower end a slot b, which is loosely yet positively engaged by the pin c, carried by the lever C, which is pivoted at c'. The outer end of lever C is attached to the operating-rod K of the semaphore-signal or other device (not shown) which is to be operated by the solenoid A. D is a dash-pot adapted to retard the movement of lever C and rod K under the influence of core B. The movable member of dash-pot D, which is shown as the outer member attached to lever C, carries a lug d, which encircles a vertical rod E. The rod E carries washers e and e', adapted to be engaged, respectively, upon the upward and downward movements of the movable member of dash-pot D. F is a bridging member, of conducting material, such as a metal disk, carried at the upper end of vertical rod E. 20 Bridging member F when vertical rod E is forced down engages the contact f. f' is a spring which bears against an insulating-block f'', carried by rod E and which holds rod E in any given position. G is a dog or catch pivoted at g on lever C and adapted to engage the pin g' when lever C is in its raised position, as shown in Fig. 1. g'' is a spring acting to hold dog G in engagement with the pin g'. As long as dog G is in engagement 25 with pin g' it serves to support the weight of lever C and the signal mechanism connected thereto, as well as the movable member of dash-pot D, and thereby relieves the core B of any downward strain thereon.

30 The operation of the electromagnet is as follows: If the actuating-coil A is deenergized and the core B, lever C, and other parts of the mechanism are at their lowest position, the bridging member F will be in engagement with the contact f. Now if magnet A is energized it will draw up its core B, moving lever C, rod K, and dash-pot D upward, until the lug d, carried by the dash-pot D, engages the collar e and raises the bridging 35 member F out of engagement with the contact f. This movement of member F acts, as will be hereinafter explained, to reduce the current flowing through the solenoid A to an amount insufficient to support the weight of lever C and the operating mechanism connected thereto. Lever C and operating-rod K consequently fall back a small amount sufficient to bring dog G into engagement with the pin g', as shown in Fig. 1. Pin g' 40 then takes the weight of lever C and the operating mechanism connected thereto while the current flowing through coil A is still sufficient to hold up the weight of core B alone. Lever C and core B are consequently maintained in the position shown, while spring f' holds bridging member F out of engagement with contacts f f'. This condition of affairs continues as long as solenoid A is energized.

45 When the circuit of the solenoid is completely broken, core B is allowed to fall, and in falling

it strikes the toe g'' of dog G, rotating it on its pivot against the pressure of spring g'' and releasing it from engagement with pin g'. Lever C consequently falls, allowing the signal to go to "danger." Just before reaching its lowest position lug d, carried by dash-pot D, engages the washer or collar e' on the shaft E and pulls down bridging member F into engagement with contact f. All the parts are 50 then in the position in which they were assumed to be at starting, and the cycle of operations is complete.

Instead of causing the bridging member F to act directly to reduce the current in the operating-magnet I provide a relay controlled by the bridging member F and controlling in turn a contact arranged to produce the desired change in the circuit of the operating-magnet. This relay may be of any well-known construction. As shown in Fig. 85 1, it consists of a magnet-coil M, provided with a suitable casing m and a vertically-movable core N, carrying an insulated bridging member O. The core N is shown in its raised position, which it maintains as long as 90 magnet-coil M is energized. When the coil is deenergized, the core falls, allowing bridging member O to come into engagement with the contacts o o.

The circuit connections are shown in Fig. 95 2, in which H represents a track-relay, with its winding connected to the rails R of the block. When the block is clear, the track-relay holds its armature h up in the position shown and releases its armature when de-energized. L represents a semaphore-blade, which is connected to the operating-rod K and which is held in clear position, as shown, when the rod K is held in its raised position by the lifting-magnet A. I represents a line-wire or other suitable source of current. J represents a resistance adapted to be inserted in the circuit with the operating-magnet A.

All the parts are shown in the positions they occupy when the block is clear. A circuit exists from the line-wire I through the resistance J, through the relay-coil M, through the operating-coil A, through relay-armature h to the continuous rail R. If a train comes on the block, short-circuiting the track-relay H, it will allow its armature h to fall, opening the circuit which has just been traced. Relay M and operating-coil A will consequently both be deenergized. Relay M will allow its bridging member O to drop into engagement with its contacts o o, and the magnet A will allow the signal-blade L to go to danger position, drawing down bridging member F into engagement with the contacts f f'. Consequently when the train passes off the block and armature h is again drawn up by the track-relay a circuit will be closed from line-wire I, through bridging member O and contacts o o, through bridging member F and contacts f f', through magnet A, and 130

through armature *h* to rail *R*. The magnet *A* is thus connected directly to the line-wire *I*, and the full voltage is impressed across its terminals. It consequently lifts rod *C*, moving signal-blade *L* to clear position. When this position is reached, bridging member *F* leaves the contacts *f f*, thereby removing a short circuit from the terminals of relay-winding *M*. Relay-winding *M* is consequently energized and draws up the bridging member *O* with a quick movement, thereby removing a short circuit from the terminals of the resistance *J*. The resistance *J* is thus thrown in series with the magnet *A*, and the current through magnet *A* is thereby reduced to an amount just sufficient to hold up its core, as has been heretofore explained.

Since the bridging member *F* removes a short circuit only from the terminals of relay *M*, which may have a winding of very low resistance, instead of from the terminals of the high resistance *J*, as in my former patent, practically no arcing occurs at the opening of bridging member *F*. Bridging member *O* is raised with a quick motion when relay *M* is energized, and consequently acts as a quick-break switch. Thus not only is all arcing eliminated, but a positive action is obtained at the exact instant when the catch is engaged with the operating-rod of the signal.

The circuit connections may be varied, and other methods of reducing the current-flow through the lifting-magnet may be employed instead of simply inserting a resistance in series with the magnet-winding.

What I claim as new, and desire to secure by Letters Patent of the United States, is—

1. In combination with an electromagnet, a movable member adapted to be raised thereby, means for retarding the movement of said member, a quick-break switch controlled by the movement of said member and adapted to decrease the current through said magnet when said member is raised, means for restraining said member when said current is decreased, and means for releasing said member when said magnet is deenergized.

2. In combination, a movable member tending to return to a given position, an electromagnet adapted to retract said member, means for retarding the movement of said member, a quick-break switch controlled by the movement of said member and adapted to decrease the current through said magnet when said member is retracted, a catch adapted to restrain said member when retracted, and means for tripping said catch when said magnet is deenergized.

3. In combination, a movable member tending to return to a given position, an electromagnet adapted to retract said member, means for retarding the movement of said member, a switch mechanically connected to said member and arranged to be operated

when said member is retracted, a relay controlled by said switch and adapted to decrease the current through said magnet, a catch for restraining said member when said current is decreased, and means for tripping said catch when said magnet is deenergized.

4. In combination with an electromagnet, a movable member adapted to be raised thereby, means for retarding the movement of said member, a resistance in series with said magnet, a relay adapted when deenergized to short-circuit said resistance, a switch mechanically connected to said member and arranged to be opened when said member is raised, said switch being arranged when closed to short-circuit said relay, a catch for restraining said member when raised, and means for tripping said catch when said magnet is deenergized.

5. In combination with an electromagnet, a movable member adapted to be raised thereby, a catch for restraining said member when raised, a quick-break switch controlled by the movement of said member and adapted to decrease the current in said magnet at the instant when said member is engaged by said catch, and means for tripping said catch when said magnet is wholly deenergized.

6. In combination, a solenoid, a core therefore, a member adapted to be moved by said core, a catch adapted to restrain said member when said core is drawn into said solenoid, and a quick-break switch controlled by the movement of said member and adapted to decrease the current through said solenoid at the instant said member is engaged by said catch, said catch being arranged to be tripped by said core when said core is released by said solenoid.

7. In combination, a solenoid, a core therefore, a member adapted to be moved by said core, a catch adapted to restrain said member when said core is drawn into said solenoid, a switch mechanically connected to said member, and arranged to open at the instant said member is engaged by said catch, and a relay controlled by said switch and adapted to decrease the current through said solenoid, said catch being arranged to be tripped by said core when said core is released by said solenoid.

8. In combination, a movable member, an electromagnet adapted to move said member, a switch arranged to be operated when said member is moved, and a relay controlled by said switch and adapted to decrease the current through said magnet.

9. In combination, a movable member, an electromagnet adapted to move said member, a resistance in circuit with the magnet-winding, a shunt around said resistance, a switch arranged to be operated when said member is moved, and a relay controlled by said switch arranged to open the shunt around said resistance.

10. In combination, a movable member, an electromagnet adapted to move said member, a switch arranged to be operated when said member is moved, and a relay controlled by said switch adapted when it is operated to include a resistance in circuit with the winding of the electromagnet.
11. In combination, a movable member, an electromagnet adapted to move said member, a switch arranged to be operated when said member is moved, and a relay controlled by said switch adapted when it is operated to increase the resistance of the circuit in which the electromagnet-winding is included.
12. In combination, a movable member tending to return to a given position, an electromagnet adapted to move said member, a switch mechanically connected to said member and arranged to be operated when said member is moved, and a relay controlled by said switch and adapted to decrease the current through said magnet.
13. In combination, a movable member
- tending to return to a given position, an electromagnet adapted to move said member, means for retarding the movement of said member, a switch mechanically connected to said member and arranged to be operated when said member is moved, and a relay controlled by said switch and adapted to decrease the current through said magnet.
14. In combination with an electromagnet, a movable member adapted to be raised thereby, means for retarding the movement of said member, a resistance in series with said magnet, a relay adapted when deenergized to short-circuit said resistance, and a switch controlling said relay and mechanically connected to said member and arranged to be opened when said member is raised.

In witness whereof I have hereunto set my hand this 6th day of January, 1905.

WALTER W. BROWN.
